CLAIM

The ornamental design for a tray, as shown and described.

DESCRIPTION

FIG. 1 is a perspective view of a tray showing my new design.

FIG. 2 is a left elevation view of the tray of FIG. 1, the right elevation view is a mirror image.

FIG. 3 is a front elevation view of the tray of FIG. 1, the rear elevation view is a mirror image.

FIG. 4 is a top plan view of the tray of FIG. 1.

FIG. 5 is a bottom plan view of the tray of FIG. 1; and, FIG. 6 is a plan view of the tray of FIG. 1 in an unfolded configuration.

The broken lines shown on the top rim of the article are shown for the purpose of illustrating exemplary fold lines which form no part of the claimed design. All other broken lines are shown for the purpose of illustrating exemplary perforations which form no part of the claimed design.
